PORTABLE AIR CONDITIONER

Walter B. Harris, Bayside, Long Island, N. Y.

Application June 2, 1938, Serial No. 211,318

3 Claims. (Cl. 261—30)

This invention relates to air conditioning apparatus, and more particularly to a self-contained and portable apparatus which will be adapted for use in homes, stores, offices, and hospitals.

5 An object of this invention is to provide an improved air conditioning apparatus having an air heating element and improved silent means causing the air to be moistened by passing through three spray zones of mistlike form inside a casing.

10 Another object of this invention is to increase the efficiency of the self-contained air conditioner by directing the air current therethrough in such a manner as to absorb and entrain a maximum quantity of moisture.

15 Another object of this invention is to provide adjustable means for varying the spray zone areas and to provide a visual indication of the intensity of humidification.

20 Another object of this invention is to provide separate fans for the circulation of the air, a lower fan causing a suction at the spray zones and an upper fan causing pressure discharge of the humidified air through an air cleaner and through a heating element.

25 Another object of this invention is to agitate the air and mist after passing through the spray zones, so as to increase the intermixture of the air and mists.

30 Another object of this invention is to make the air conditioning mechanism including the motor, fans, pumping unit, pump controls, heating element, air cleaner, grill, electric connections and the cover, removable as a unit from the outer casing and basin for cleaning purposes.

35 With the above and other objects in view, the invention will be hereinafter more particularly described, and the combination and arrangement of parts will be shown in the accompanying drawings and pointed out in the claims which form part of this specification.

40 Reference will now be had to the drawings, wherein like numerals of reference designate corresponding parts throughout the several views, in which:

45 Figure 1 is a plan view of a preferred form of air conditioner.

Figure 2 is a vertical cross-sectional view of the air conditioner, the section being taken as on line 2—2 in Figure 1.

50 Figure 3 is a plan view of a preferred type of pump for the air conditioner.

Figure 4 is a vertical elevation of the pump.

55 Figure 5 is a vertical elevation of the pump partly broken away to show the inner structure.

Figure 6 is a fragmentary bottom view of the pump.

Figure 7 shows a fragmentary portion of the lower end of the pump, on an enlarged scale.

Figure 8 is a fragmentary vertical cross-sectional view of the air conditioner showing the spray regulator set for humidifying fifty per cent of the air passing through the air conditioner.

Figure 9 is a sectional plan view of the spray forming portion of the air conditioner, the section being taken as on line 9—9 in Figure 2.

Figure 10 is a fragmentary vertical cross-sectional view of the air conditioner showing the spray regulator, shown in Figures 2 and 8, in closed position.

Figure 11 is a fragmentary vertical cross-sectional view of the air conditioner showing a spray shield.

In the illustrated embodiment of the invention, the numeral 10 indicates the portable air conditioner comprising a casing 11 having louvers 12 in its sides. A tubular member 13 of smaller cross-section than the casing 11, has been secured centrally of the casing and stops short of the lower end of the casing and provides a transverse passage 14. Air entering through the louvers passes downwardly through an annular duct 15 formed between the tubular member 13 and the casing 11 and then through the passage 14 and upwardly through the tubular member 13.

The lower end 16 of the casing 11 has been made water tight and forms a storage basin for a liquid 17. An electric motor 18 has been mounted vertically and centrally in the tubular member 13 and has a fan 19 secured at the lower portion of the motor shaft 20. A fan 21 has been secured to the upper end of the motor shaft.

A pump 22 has been secured at the lower end of the shaft 20 and is immersed in the liquid 17. The pump 22, best shown in Figures 3, 4 and 5, comprises an outer casing 25 having bosses 26 at its upper end. The pump casing 25 is secured to a spray disk 27 having a hub 28 secured to the shaft 20. The lower end of the casing 25 has a lip 29 of spiral formation. The disk 27 has an internally threaded lower hub 30 serving to receive a threaded stem 31 of a spirally threaded cone 32. The thread 33 extends from the lower to the upper ends of the cone 32 and is substantially in contact with the inner surface of the pump casing 25. The lowermost end of the thread 33 starts at the lowermost tip of the lip 29 of the pump casing 25.

The lip 29 encloses the lowermost end of the

thread 33 which projects from a horizontal bottom 35 of the casing 25 thereby forming a scoop 36. Under operating conditions the revolving scoop 36 continuously picks up water which is carried by the thread 33 to the upper elevation of the pump 22 and is discharged through peripheral openings 37 in the disk 27.

The water discharged through the openings 37 travels to the periphery of the disk 27 from which it is thrown by centrifugal force in the form of a spray against the inner surface of the cylindrical member and against the inner surface of the casing. It is to be noted that the level at which the water leaves the disk 27 is in line with the lower edge of the cylindrical member.

The lower fan 19 is designed to cause an air suction upwardly into the cylindrical member 13. The blades of the upper fan 21 have a greater pitch than the blades of the lower fan 19 so that it is adapted to pick up the moving air from the fan 19 and further increase the velocity of the air stream. The fan 19 draws air through the louvers 12 and through the passages 15 and 14.

The air suction lifts the lighter spray particles upwards and into contact with the inner surface of the cylindrical member 13 forming a spray curtain 38 across the horizontal bottom opening 39 of the member 13.

The heavier spray particles tend to drop as they leave the disk 27 and come into contact with the inner surface of the casing 11, forming a heavier spray curtain 40 over the annular cross-sectional area of the duct 15.

It is to be noted that the liquid spray particles contacting the inner surface of the cylindrical member 13 condense on the cylindrical walls thereof and fall down in the form of a cylindrical shower curtain 41 through which the incoming air must pass. There has thus been provided three spray zones 38, 40 and 41.

The blades of the suction fan 19 revolving in the air and entrained mist inside the stationary tubular member 13 creates a whirling motion and the blades of the fan 19 agitate the air and mist causing the mixture to be broken up into finer particles thus increasing the intermixture.

The outer periphery of the motor 18 is much smaller than the inner periphery of the tubular member 13 providing an annular passage 45 upwards around the motor. The motor 18 is secured to the tubular member 13 by radial braces 46 which also function to break up the upward whirling motion of the air and causing turbulence in the humidified air stream. The fan 21 propels the humidified air upwards through a dry spun glass air cleaner 47 and through an electric heater 48 having horizontally positioned heating elements 49, 49 and then through an opening 50 at the top of the cylindrical member 13. The fan 21 serves to remove entrained particles of free liquid from the humidified air. The dry spun glass air cleaner 47 is constructed to provide interstices between adjacent fibres of glass. The humidified air from the fan 21 passes through the dry cleaner 47 and any remaining wet foreign matter in the humidified air is deposited upon the said cleaner.

The heater 48 and the electric motor 18 may be provided with electric current by means of electric wiring 51 and an electric plug 52 which may be connected to any supply of electric current. The heater may be connected to a source of electric current supply independent of the electric current supply to the motor. During cool or damp weather conditions, the motor and heat-

er are operated simultaneously, to remove the excess moisture from the air. During hot, dry weather the heater is shut off.

As shown in Figure 2, there has been provided a spray regulator 55 comprising a dished member 56 of slightly larger diameter than the pump disk 27. The dished member 56 has an integral extension 57 which is hinged at 58 to the lower end portion of the cylindrical member 13. The dished member 56 has an aperture 54 centrally thereof of larger diameter than the motor shaft to permit tilting of the member 56 about the hinge 58.

An arm 59 integral with the member 56 and positioned diametrically opposite the extension 57 has its free end hingedly connected to a vertical rod 60. The rod 60 extends upwardly through the top of the air conditioner 10, and has a knob 61 at the upper end thereof. Notches 62 at the upper end of the rod 60 make it possible for the operator to grasp the knob 61 and move the rod up or down so as to cover or uncover the disk 27 and thus control the spray zone areas and the intensity of humidification.

The operator may, by interlocking one of the notches 62 with the cover plate 63, vary the angular position of the member 56 with relation to the disk 27 of the pump 22 to provide the required humidification of the air being conditioned. It is to be noted that the operator may adjust the dished member 56 so as to entirely cut off and eliminate the spray curtains in the air passages.

The disk 27 of the pump 22 is shown as in dished form. This dish-shape permits a quantity of water to collect therein until it reaches the upper elevation of the dish when the water, under the action of centrifugal force, overflows and leaves the dish in a continuous spray.

It is to be noted that by providing two fans in series on the motor shaft but in spaced relation on opposite sides of the motor and with the discharge fan having blades of greater pitch than the suction fan and both fans within a tubular casing forming a tunnel of slightly larger diameter than the outer diameters of the fans, that with these fans, arranged as shown, it is possible to discharge the equivalent amount of air normally requiring a relatively larger fan which would increase the size of the air conditioner.

As shown in Figure 2, I have provided a baffle-plate 65 located centrally of the casing 11 and fixed thereto. The baffle-plate 65 serves to prevent swirling of the water in the basin 17.

Figures 8 and 9 show the spray regulator 55 set in angular relation with the pump disk 27 so as to extend below one-half of the upper peripheral edge of the disk. This position of the spray regulator cuts off the spray from one-half of the area of the three spray zones. As best shown by the arrow in Figure 8, the air passes through one-half the surface area of the air conditioner without passing through the three sprays.

Figure 10 shows the spray regulator 55 set in horizontal position over the disk 27 of the pump 22. It will be noted that this horizontal position of the spray regulator 55 cuts off all the sprays 38, 40 and 41. The spray leaving the disk 27 and identified by the numeral 66 is directed downward and returns to the liquid storage basin 17, in the form of heavy drops without passing through the incoming air. The air is thus not humidified or washed but is dry cleaned by passing through the dry air cleaner 47 and may be heated by the heater 48.

Figure 11 shows a spray shield 67 of cylindrical

form and having apertures 68, 68 at its lower elevation. The spray shield 67 may be secured to the bottom plate of the casing and preferably extends upwardly slightly above the bottom edge 5 of the spray regulator 55 when in horizontal position. The top edge of the spray shield 67 is slightly below the top edge of the disk 27. The spray shield 67 is used for positively preventing any of the spray 66 returning to the basin, from being thrown out into the air passage 14.

When the spray regulator 55 is raised into angular position, as shown in Figure 8, the bottom edge 69 of the regulator 55 rises and permits the spray to leave the disk 27 and function in a manner corresponding to the disclosures in Figures 15 8 and 9.

A float 70 has an indicator at its upper end. This indicator is seen through an opening 71 in the casing 11 and indicates the level of the liquid 20 in the basin 17.

In accordance with the patent statutes I have described and illustrated the preferred embodiment of my invention, but it will be understood that various changes and modifications can be 25 made therein without departing from the spirit of the invention as defined by the appended claims.

I claim:

1. In an air conditioner having an air passage 30 of substantially constant cross-sectional area and means for forming a spray curtain, upright cylindrical baffle means for subdividing said spray curtain into lighter and heavier spray curtains positioned in spaced relation across said 35 passage, a motor mounted vertically in said cylindrical baffle means, upper and lower fans secured in spaced relation at opposite ends of the motor-shaft, the blades of said upper fan being of greater pitch than the blades of said lower fan, 40 an adjustable spray regulating means for controlling the areas of said spray curtains, said

spray regulating means being designed to gradually cut off the area of said spray curtains and the humidification area of said air passage.

2. The invention as defined in claim 1, where- 5 in means is provided intermediate said fans to cause turbulence in the humidified air stream.

3. In an air conditioner comprising an upright casing having louvers in its sides, an upright cylindrical baffle mounted centrally of said cas- 10 ing, the lower edge of said cylindrical baffle being in spaced relation above the bottom of said cas- ing, the walls of said cylindrical baffle and said casing being in parallel relation, a liquid storage chamber in the lower portion of said casing, a 15 pump immersed in said liquid and comprising a spray discharging disk at its upper elevation, said disk being at the level of the lower edge of said cylindrical baffle, said disk being adapted for throwing a spray against the inner surface of 20 said cylindrical baffle, a portion of said spray being deflected by said cylindrical baffle in an upward direction, a portion of said spray forming a heavy spray curtain passing across the cross-sectional area between said casing and said cylindrical baffle, a portion of said spray 25 forming an upright cylindrical shower curtain falling downwardly from said cylindrical baffle walls, said air conditioner comprising an air duct positioned so as to cause the incoming air to pass through all said sprays, an adjustable spray reg- 30 ularizing means for controlling the areas of said sprays, said spray regulating means being in co-acting relation with said pump disk and being designed to gradually enclose and cut off the area of said sprays and the humidification area 35 of said air passage, and motor driven fans in spaced and superposed relation in said cylindrical baffle for circulating air through said air conditioner.

WALTER B. HARRIS. 40
